US00D967572S

(12) **United States Design Patent** (10) **Patent No.:** **US D967,572 S**
(45) **Date of Patent:** **** Oct. 18, 2022**

(54) **SHOE DRYER**

(71) Applicant: **Chunyu Zhang**, Shanxi (CN)

(72) Inventor: **Chunyu Zhang**, Shanxi (CN)

(**) Term: **15 Years**

(21) Appl. No.: **29/809,381**

(22) Filed: **Sep. 28, 2021**

(51) LOC (13) Cl. **15-05**

(52) U.S. Cl.

USPC **D32/8**; D32/58

(58) **Field of Classification Search**

USPC D32/8, 14.1, 25, 55, 58, 59; D15/199

CPC A43D 3/1408; A43D 117/00; A43D 95/10;

(57) **CLAIM**

The claim the ornamental design for a shoe dryer, as shown and described.

DESCRIPTION

FIG. 1 is a front elevational view of a shoe dryer showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a bottom perspective view thereof;

FIG. 8 is another perspective view thereof;

FIG. 9 is a top rear perspective view of the shoe dryer shown in an open configuration;

FIG. 10 is an enlarged detail view of area 10 in FIG. 7; and, FIG. 11 is an enlarged detail view of area 11 in FIG. 9.

The broken lines in the figures are for the purposes of illustrating portions of the shoe dryer, which form no part of the claimed design.

1 Claim, 11 Drawing Sheets

FIG. 11
